MOTION CONTROLLING MEANS FOR SLIDE RULES

Arthur F. Eckel, Evanston, Ill., assignor to Louise Pickett, La Grange, and Myrtle Eckel, Evanston, Ill.

Application August 20, 1947, Serial No. 769,689

10 Claims. (Cl. 235—70)

1

This invention relates to slide rules, and has particularly to do with means for controlling the movements of the slider and cursor thereof.

It is well known that in the use of slide rules time is lost in attempting to adjust the slider in accurate register with the stator, and likewise in adjusting the cursor in register with the slider and stator. Often it is necessary to adjust either of these movable elements to a micrometric degree, but this has been difficult.

An object of the present invention is, therefore, the provision of means for enabling the user of a slide rule to produce micrometric movements of the movable elements quickly and to the exact degree desired.

Formerly in the use of slide rules, it has been found that when either the slider or the cursor has been set in a desired position and the other is then moved, the first one set often becomes dislodged from its set position.

It is, therefore, another object of the present invention to provide means for locking the slider and the cursor in their set positions so that they will not be moved accidentally, but only when the user desires to deliberately move them.

It is a still further object to provide a novel type of slider for a slide rule which in normal position is locked relative to the stator, and which can be unlocked by the user when it is desired to move the slider.

The slider of the slide rule of the present invention is composed of two longitudinally extending parts having inter-engaging wedge surfaces, and spring means biasing the parts in directions effective for bringing the parts into friction engagement with the respective elements of the stator, thereby locking the slider in place.

Another object is the provision of simple release means for releasing the locking means of the slider so that the user can readily slide the slider.

Still another object of the invention is the provision of a novel slider in which the scale pieces thereon are movable to a limited extent along the slider, and this movement is controlled by a means for accomplishing movements of the scale pieces in micrometric degrees. The slider is moved to the approximate position desired and after this position is established the scale pieces on the slider can be adjusted in extremely fine degrees to bring the scale pieces thereon in perfect register with the scale pieces on the stator.

Still another object is the provision of adjustable stop means on the slider to form limits to which the scale pieces thereon can be adjusted.

2

It has also been well known that in the use of previous types of slide rules, the cursor was many times likely to be accidentally moved from its position after the user has once set it.

5 It is, therefore, another object of the present invention to provide locking means for the cursor which is effective for securing the cursor in a position after being set, so that it will not be accidentally moved therefrom.

10 Another object is the provision of a novel locking means for the cursor of a slide rule which can be provided in the cursor and adapted to cooperate with the stator without any special design of the stator elements for this purpose.

15 A further object is the provision of means for accomplishing micrometric movements of the cursor. The user, when desiring to make such movements, releases the locking means and such movements are made under the immediate at-

20 tention of the user and at all other times the locking means of the cursor is normally in locking engagement with the slide rule.

Still another object of the invention is the provision of adjustable limit means for limiting the extent of movement of the cursor, this feature being convenient in fixing the point at the end of the rule to which the cursor can be moved so that the cursor will readily be in register with the end of the scale marking on the stator, and can be quickly moved to that position without the necessity of using undue care or losing time in so setting the cursor.

in so setting the cursor.

With these and other objects in view, my invention consists in the construction, arrangement, and combination of the various parts of my device whereby the objects contemplated are attained, as hereinafter more fully set forth, pointed out in my claims, and illustrated in the accompanying drawings wherein:

The slider

Referring in detail to the drawings and particularly Figures 1 to 9 inclusive, the slide rule is composed of a stator 16, a slider 18 and a cursor 20. The stator 16, as is usual in slide rules, is made up of a pair of stator elements 22 and 24, which are elongated flat elements, secured together in spaced relation by end pieces 26 which are secured across the respective ends of the stator elements as by screws or other means for forming a space between the stator elements for the slider. The stator elements 22 and 24 may be made of metal, plastic, or other material, and the opposite faces are provided with the usual scale markings thereon.

The stator elements 22 and 24 are provided on their outer edge surfaces with longitudinally extending grooves or channels 28 and 30 for cooperation with tongue elements of the cursor. The groove 28 is adapted for cooperation with the locking means of the cursor referred to above, and which will be explained in detail later and, for this reason, the groove 28 is preferably rectangular in cross-section. The groove 30 may also be rectangular in cross-section for purposes of symmetry, although the shape of the latter may be different if desired. The stator elements 22 and 24 are also provided with groove elements 32 on their inner edge surfaces for cooperation with tongue elements on the slider. Other details of the stator elements may be formed, as desired, for various purposes, the foregoing being designed for purposes of the improvements of the present invention.

The slider 18 is made up of a central core member 34 and side scale pieces 36 and 38 which are provided with appropriate scale markings for cooperation with the scale markings on the stator.

The construction of the core member 34 of the slider may be observed more readily from Figures 1, 2, and 6, wherein it will be seen that the core member is made up of two separate pieces 40 and 42. The pieces 40 and 42 have cooperating wedge surfaces indicated by the parting line 44, which divides the core member longitudinally of the rule in such a manner that the wedge surfaces of the pieces face each other; each of the wedge pieces 40 and 42 has a large end at one end of the slider terminating normally substantially flush with the small end of the other wedge piece.

The wedge piece 40 of the slider is provided with a central longitudinal groove 46 which may be cut in from one of the flat surfaces thereof, as for instance the top surface of Figure 6. This groove may also be seen in Figure 7. Toward the end of the wedge piece 40 at the left of Figure 6

is an enlarged opening 48 disposed transversely of the groove 46 and extending through the respective wedge piece. Substantially centrally longitudinally of the wedge piece 40 is a cut-out portion 50 which also extends through the wedge piece 40 and is cut downwardly from the wedge surface thereof.

The wedge piece 42 for the most part is symmetrical with the wedge piece 40, having a longitudinal groove 52 centrally of its flat surface thereof similar to the groove 46 but wider than the latter, and an opening 54 at the larger end thereof and to the right in Figure 6 similar to the opening 48 at the opposite end of the piece 40. Substantially centrally of the wedge piece 42 is an enlarged cut-out portion 56 extending through the wedge piece 42 and cut from the wedge surface thereof, this opening 56 being of greater dimension longitudinally than the opening 50.

Formed along the outer edge surfaces of the wedge pieces 40 and 42 of the slider are V-shaped tongue elements 58 and 60 extending longitudinally thereof. These tongue elements 58 and 60 are adapted to slide in the groove elements 32 in the inner edges of the stator elements. The tongue element 60 has a cut-out portion 62 centrally thereof in register with a hole 64 extending through the wedge piece 42 and into the cut-out portion 56 substantially centrally of the latter.

The wedge portion 42 is provided with cut-out cavities 66 in the wedge surface thereof, disposed parallel with its wedge surface, or the line 44 between the facing wedge surfaces of the wedge pieces 40 and 42. The wedge piece 40 is provided with a projection 68 extending into each of the cut-out portions 66 at a point in the latter toward the right of Figure 6. A compression spring 70 is positioned in each of the cut-out portions 66 and biased between the respective projection 68 and the end of the cut-out portion farthest from the projection. The springs 70, therefore, bias the wedge pieces 44 in such a manner as to separate the wedge pieces, that is, the wedge piece 40 to the right and the wedge piece 42 to the left (Figure 6) spreading the wedge pieces in a direction perpendicular to the length thereof. If desired, the projections 68 may be adjustable along the wedge surface of the piece 40 and in the cavities 66.

A shaft 72 is positioned in the grooves or channels 46 and 52 and supports a worm gear 74 centrally thereof. The worm gear 74 is thereby disposed in the cut-out portion 50 in the wedge piece 40 and is secured against rotation on the shaft by means of a set screw 76. Preferably the set screw 76 is of the Allen head type, access to which may be gained through the drill hole 64 by means of a small diameter wrench. The worm gear 74 is of such a length to fit in the cut-out portion 50 snugly therein, the end portions of the cut-out portion forming stop means for limiting movement of the worm gear and the shaft longitudinally of the slider. Knurled turn wheels 78 are secured to the shaft 72 and positioned in the cut-out portions 48 and 54. The wheels 78 are secured against rotation on the shaft 72 by means of set screws 80. The wheels 78 are adapted for rotating the shaft 72 and are exposed to access of the user as will be explained more fully later.

Each of the wedge pieces 40 and 42 of the slider on each side thereof is provided with lateral extensions 82 having inclined surfaces 84, these surfaces on each side of the slider sloping toward

each other outwardly of the slider. The surfaces 84, which are disposed on the same side of the slider, form groove elements adapted to receive tongue elements 86 on the scale pieces 36 and 38, by means of which the scale pieces are secured to the core of the slider.

Each of the scale pieces 36 and 38 is provided on its inner surface, and in the respective tongue element 86 with a concave portion indicated generally at 88 (Figures 7 and 8). The concave portions are disposed substantially centrally longitudinally of the scale pieces are adapted to fit over the worm gear 74 on the shaft 72. The concave portions 88 are provided with threads 90 to receive the threads of the worm gear 74. The concave portions 88 are longer than the worm gear 74, and when the scale pieces are secured to the core element of the slider, the worm gear, on turning thereof, is effective for sliding the scale pieces longitudinally of the slider. The scale pieces and the extensions 82 forming the groove elements, terminate short of the wheels 78 as will be observed from Figure 1, so that the wheels 78 are exposed to easy access by the user.

The means for actuating the locking means of the slider comprises a pair of plates at each end of the slider. Each pair of plates comprises a fixed plate 92 and a hinged plate 94, secured on the opposite flat sides of the slider. The fixed plate 92 is secured in each case to the large end of the wedge piece 40 or 42 disposed at that end, by means of screws or other desired means. The hinged plate 94 is provided with an extension 96 which fits in between the arms 98 of a plate 100 secured to the large end of the respective wedge piece, by means of screws, or other desired means. The plate 94 may be hinged by means of a convenient pin extending through the arms 98 of the plate 100 and the extension 96. The small end of each wedge piece is free to slide between the small plate 100 and the fixed plate 92. The hinged plate 94 is provided with an extension or foot 102 extending toward the plate 92 and in position for engaging the end surface of the small end of the respective wedge element. The width of the foot 102 in the direction of the width of the plate is substantially coextensive with the width in that direction of the respective small end of the wedge piece. The hinged plate 94 is biased away from the fixed plate 92 by means of a compression spring 104 disposed between the plates. The hinge between the hinged plate 94 and the plate 100 may be a conventional hinge having a stop to limit the outward swinging of the plate 94 to a position parallel with the fixed plate 92. The core may be provided with an inclined cut-off portion 105 (Figure 9) to accommodate the downward swinging movement of the portion 96 of the plate 94 when the latter is depressed.

Adjustable stop means 106 is secured to the core member 34 of the slider at each end of the respective scale pieces 36 and 38 and on both sides of the slider for limiting the longitudinal movement of the scale pieces. The stop means 106 may be a disk, either circular or irregularly shaped, and secured to the core of the slider by means of a screw positioned eccentric to the disk. The screw may be loosened and the disk positioned in various positions of angular adjustment, thereby acting as a cam having different surfaces engageable by the scale piece for varying the limit of movement of the latter. The screws securing the disks 106 are positioned offset with respect to the grooves 46 and 52 so that the screws

can be run into the core of the slider a sufficient extent to be properly secured therein.

Use and operation of the slider

5 The groove elements formed by the inclined surfaces 84 in the wedge elements 40 and 42, and the cooperating tongue elements 86 in the scale pieces 36 and 38, can have such an inclination that only a slight extent of wedging movement is necessary for inserting the scale pieces and securing them in place. In assembling the slider, the wedge elements are placed together with their wedging surfaces interengaging and slid relative to one another so that the groove elements thereof formed by the inclined surfaces 84, are spread wide enough for the insertion of the tongue elements 86 on the scale pieces. One scale piece is then put in place by inserting the tongue element 86 thereof into the groove element of the wedge pieces. The first scale piece may be, for example, 38 which is to be placed on the underside of the slider as viewed in Figure 6. Then the worm gear 74 is inserted in position in the cut-out portion 50 and a small diameter wrench inserted through the hole 64 and into the set screw 76. The next step is to place the compression springs 70 in the cut-out portions 60 as illustrated in Figure 6. Then the scale piece 36 is placed on top of the slider and the two wedge pieces slid so that the groove elements in the wedge pieces are brought into engagement with the tongue elements on the scale pieces. The initial movement of sliding the wedge pieces may have moved the grooves 46 and 52 out of alignment but, after the two scale pieces are placed on the core, the wedge pieces are brought back to the positions where the grooves 46 and 52 are in alignment. The wheels 78 are then inserted into the cut-out portions 48 and 54. Then the shaft 72 is inserted into the groove 52 which opens out of the end of the wedge piece and inserted through the respective wheel 78, the worm gear 74, the groove 46, and finally through the wheel 78 at the far end. The wrench previously inserted through the hole 64 and into the set screw 76 is utilized for tightening the worm gear 74 onto the shaft. Then the set screws 80 in the wheels 78 are tightened. After these steps have been completed, the plates 92 and 94 are secured on the large ends of the wedge pieces 40 and 42. Thereafter, the stop means 106 can be secured in place.

55 The thickness through the slider and scale pieces 36 and 38 is substantially the same thickness as through the plates 92 and 94, this thickness being also the thickness of the stator pieces 22 and 24 so that the slider can be easily slid through the end pieces 26. If desired, the end pieces 26 can be provided with arcuate cut-out portions 108 to accommodate wheels 78 of a diameter greater than the thickness of the assembled slider.

60 The compression springs 70 in the cut-out portions 60 normally bias the wedge pieces 40 and 42 in directions such that the wedge surfaces 65 thereof force the wedge elements into engagement with the stator elements 22 and 24. The extent of movement sideways into engagement with the stator elements need be practically only an infinitesimal amount for purposes of friction locking the slider with the stator.

70 When the user wishes to slide the slider, he merely presses together on the plates 92 and 94 at either end of the slider, and the relative movement together of these plates forces the wedge elements 40 and 42 in the direction opposite to that

biased by the springs 10, thereby releasing the friction engagement between the wedge pieces and the stator elements and enabling the slider to be easily slid through the rule. This relative movement is indicated to an exaggerated degree in Figure 5. The plates 92 and 94 being positioned at both ends of the slider, the user can quickly release the locking means of the slider and, after the slider is moved to the approximate position desired, he releases the plates and the slider is effectively locked in the position set.

After the approximate position of the slider is set by the user, and the scale marking on the slider is not in exact register with the intended marking on the stator element, the user merely turns one of the wheels 78. This rotation of the wheels 78, acting through the shaft 72, rotates the worm gear 74, which, being secured against longitudinal movement in the slider by means of its close fit in the cut-out portion 50, adjusts the scale pieces longitudinally along the slider. Rotation of the worm gear acting on the threads 90 in the scale pieces produces micrometric movements of the scale pieces by means of which the user can produce exact adjustment of the scale pieces.

The scale pieces 36 and 38 may be of metal, as actually produced in many cases; and, when made of metal, the threads 90 can be cut directly into the material forming the scale pieces, eliminating the necessity for insertion of a hard surface bearing material.

The cursor

The cursor 20 referred to generally above comprises a pair of transparent side plates 110 as is usual in cursors, secured together by a spacer element 112 at one end engaging the stator element 24. The spacer 112 is provided with a tongue element 114 which is received in and slides in the groove 28 in the stator element 24. The opposite ends of the side plates 110 contain the locking means and micrometric movement means for controlling the movements of the cursor. This mechanism is referred to generally at 116.

Referring particularly to Figures 10 to 14, this mechanism includes a lever 118 pivoted at 120 in a pin supported by the side plates 110. The lever 118 has an upwardly extending short portion 121 which extends up into the groove 28 in the stator element 22. The lever 118 also includes a long portion 122 which extends horizontally along the stator element 22 between the side plates 110 and has a terminal portion 124 extending slightly beyond the side plates 110. A pin 126 is supported by the lever 118 at a point substantially centrally of the cursor longitudinally of the rule, and this pin 126 supports a pair of rollers 128, one on each side of the lever. The pin 126 is fixedly secured in the lever and the outer ends thereof extend through slots 130 formed in the rollers 128 of an extent vertically slightly larger than the diameter of the pin 126.

Spacers 132 are positioned on either side of the lever 122 and extend from the bottom edge of the side plates 110 up to and in engagement with the lower edge of the stator element 22 on opposite sides of the groove 28. The spacers 132 may be secured in place therein by means of the pin 126 on which the lever 118 is hinged, and by another screw 134 at the opposite side of the cursor at a point above the extending portion 124 of the lever. The side spacers 132 are provided with central cut-out portions 136 for receiving the rollers 128 therein, the lower end of the cut-out

portions being rounded to conform to the shape of the rollers. Secured to and between the side spacers 132 is another member 138 disposed above the lever 124 and extending from the side of the cursor having the extension 124 of the lever to a point slightly short of the upstanding leg portion 121 of the lever. This member 138 is positioned in register with the undersurface of the groove 28 in the stator element 22. A compression spring 140 is biased between member 138 and the lever 118, being secured in place in sockets therein and effective for biasing the leg portion 122 of the lever 118 downwardly. A pair of wedge elements 142 and 144 are positioned above and secured to the member 138 in position to be received in the groove 28 in the stator. The wedge elements 142 and 144 are divided by a line 146 (Figure 12) forming interengaging wedge surfaces. The wedge element 142 may be a part of the member 138 or it may be a separate piece and secured thereto. The wedge element 144 is separate from the element 138 and is secured thereto by means of a screw 148 threaded through an elongated slot 150 which is disposed parallel with the dividing line 146. The slot 150, as illustrated in Figures 12 and 14, is exaggerated in extent, since the slot need be only slightly larger than the diameter of the screw 148. The wedge member 144 is adapted to have relative motion with respect to the wedge piece 142 as will be explained later in detail, and the slot 150 is adapted to slide over the screw 148 in such sliding movements. The wedge piece 142 is provided with a cut-out portion or cavity in its wedge surface and is adapted to receive adjacent one end thereof a projection 153 secured to the wedge surface of the wedge piece 144. The cavity 152 may be disposed intermediate the upper and lower surfaces of the wedge members (Figure 14), or it may be cut in the top surface of the wedge member as viewed in Figure 12. A compression spring 154 is interposed in the cavity 152 between the projection 153 and the end of the cavity farthest therefrom, and is effective for reacting between the wedge pieces biasing the wedge member 144 to the right (acting through the projection 153) and the wedge member 142 to the left (Figure 12), or in directions contracting the two elements away from the side walls of the groove 28 in the stator element.

Stop means 156 are provided in the groove 28 to adjustably limit the extent of movement of the cursor. Each stop means 156 may be an insert filling the groove and is provided with an adjustable set screw 158.

Use and operation of the cursor

In any undisturbed position of the cursor 20, the compression spring 140 biases the long leg 122 of the lever 118 downwardly, rotating the lever 118 counterclockwise and bringing the short leg 121 thereof into engagement with the wedge element 144. This action biases the wedge element 144 to the left as viewed in Figure 12, relatively sliding the wedge elements 142 and 144 together and effectively spreading them sideways into engagement with the side surfaces of the groove 28 in the stator element. The compression spring 140 is strong enough to overcome the counteracting compression spring 154, thus locking the cursor in the particular position set on the slide rule.

When the user desires to slide the cursor along the rule, he presses the lever 118 by means of the extension 124 which swings the short leg 121

of the lever outwardly from and releases the pressure against the wedge element 144. Thereafter, the compression spring 154 becomes effective for causing relative sliding movement between the wedge elements longitudinally of the groove 28 whereby the wedge elements are contracted transversely, bringing them out of frictional engagement with the side surfaces of the groove 28. The cursor can then be easily slid along the rule and, when it is brought to the approximate position desired, the lever 118 is released and the cursor is locked in the position set.

The means for producing micrometric movements of the cursor consists of the roller means 128. The user presses on the rollers 128 which are normally out of engagement with the edge surface of the stator element 22. The rollers, when pressed against the stator, come into engagement with the latter and, at the same time, the pin 126 forces the lever 118 clockwise and releases the pressure exerted against the wedge element 144. The locking means is thus released and the user can roll the rollers along the stator element, the cursor then being moved along the rule at a reduced rate of movement.

The set screws 158 may be adjusted through the inserts 156 in one direction or the other longitudinally of the grooves to adjustably limit the extent of movement of the cursor to position the index line thereof over the end mark of the scale markings on the rule. Such stop means are shown in the groove 28 but, if desired, they may be provided in the groove 30 so that the stop means does not interfere with the proper operation of the short arm 121 of the lever 118.

If the diameter of the wheel 78 is such as to extend beyond the dimensions of the scale pieces 36 and 38 in the slider, the side plates 110 of the cursor may be provided with arcuate cut-out portions 160.

While I have herein shown and described a preferred embodiment of my invention, manifestly it is susceptible of modification and rearrangement of the parts without departing from the spirit and scope thereof. I do not therefore, wish to be understood as limiting my invention to the precise form herein disclosed, except as I may be so limited by the appended claims.

I claim as my invention:

1. In a slide rule having a pair of stator elements and a slider slidable therebetween, said slider comprising a core member formed of separable parts, said parts being engageable with said stator elements, means biasing said parts into engagement with said stator elements, releasing means carried by the slider and adapted to move said parts out of engagement with said stator elements, and a scale piece carried on each side of the core member.

2. In a slide rule having a pair of stator elements and a slider slidable therebetween, said slider comprising a core member formed of separable parts, said parts being engageable with said stator elements, means biasing said parts into engagement with said stator elements, releasing means carried by one of said parts and engageable with the other part for moving said parts out of engagement with the respective stator elements, and a scale piece carried on each side of said core member.

3. In a slide rule having a pair of stator elements and a slider slidable therebetween, said slider comprising a core member and a scale piece on each side thereof, said core member being formed of separable, oppositely disposed,

wedge-shaped parts extending longitudinally the length of the slider, each of said parts being engageable with one of said stator elements, said parts having interengaging inclined surfaces, biasing means interacting between said parts and biasing the parts in opposite directions longitudinally of the rule causing said inclined surfaces to force the parts outwardly into engagement with the respective stator elements, and releasing means carried by the slider adapted to move said parts in directions respectively opposite to the movements caused by said biasing means.

4. In a slide rule having a pair of stator elements and a slider slidable therebetween, said slider comprising a core member and a scale piece on each side thereof said core member being formed of separable oppositely disposed, wedge-shaped parts extending longitudinally the length of the slider, each of said parts being engageable with one of said stator elements, said parts having interengaging inclined surfaces, biasing means interacting between said parts and biasing the parts in opposite directions longitudinally of the rule causing said inclined surfaces to force the parts outwardly into engagement with the respective stator elements, and releasing means carried by the large end of each wedge-shaped part, each releasing means being operable to engage the adjacent small end of the other wedge-shaped part and interact between the two parts for moving the parts in directions respectively opposite to the movements caused by said biasing means, said releasing means being operable independently of each other.

5. In a slide rule having a pair of stator elements and a slider slidable therebetween, said slider comprising a core member and a scale piece on each side thereof, said core member being formed of separable, oppositely disposed, wedge-shaped parts extending longitudinally the length of the slider, each of said parts being engageable with one of said stator elements, said parts having interengaging inclined surfaces, biasing means interacting between said parts and biasing the parts in opposite directions longitudinally of the rule causing said inclined surfaces to force the parts outwardly into engagement with the respective stator elements, and releasing means carried by the large end of each wedge-shaped part, each releasing means comprising a pair of spaced plates extending longitudinally outwardly from the end of the slider and within the confines of the longitudinal projection thereof, one of said plates being rigidly fixed to said wedge-shaped part and the other plate being hinged thereto, said hinged plate having a lateral extension engageable with the adjacent small end of the other wedge-shaped part, said hinged plate being swingable toward said fixed plate whereby said lateral extension bears against the other wedge-shaped part and the hinged plate interacts between the two wedge-shaped parts and moves the latter in directions respectively opposite to the movements caused by said biasing means.

6. A slide rule comprising a pair of stator elements and a slider slidable therebetween, said slider having portions expandable and contractible toward and away from said stator elements, biasing means operable to expand said portions, means operable to contract said portions, and a scale piece on each side of the core member, said scale pieces and core member having interlocking dovetail tongue and groove elements for retaining the scale pieces on the core member, said

scale pieces being movable longitudinally on said core member.

7. In a slide rule having a pair of stator elements and a slider slidable therebetween, said slider comprising a core member formed of separable parts, said parts being engageable with said stator elements, means biasing said parts into engagement with said stator elements, releasing means carried by the slider and adapted to move said parts out of engagement with said stator elements, and a scale piece on each side of said core member, said scale pieces and the parts of said core member having interlocking dovetail tongue and groove elements for retaining said scale pieces on said core member, the extent of inclination of the interengaging inclined surfaces of said tongue and groove elements being greater than the extent of movement of said parts toward and from said stator elements.

8. In a slide rule having a pair of stator elements and a slider slidable therebetween, said slider comprising a core member, a scale piece carried on each side of said core member, said scale pieces being movable longitudinally of said core member, a shaft rotatably mounted in said core member, means secured to said shaft extending out of said core member for rotation of said shaft, and means on said shaft and scale pieces cooperable on rotation of said shaft for micrometer adjustment of said scale pieces longitudinally of said core member.

9. In a slide rule having a pair of stator elements and a cursor slidable thereover, said cursor having a pair of wedge shape portions adapted to engage one of said stator elements, said wedge shape portions having interengaging inclined surfaces and adapted to have relative sliding movement for expansion and contraction thereof, biasing means operable for contracting said wedge

shape portions, biasing means operable for expanding said wedge shape portions, and means for inactivating said last-named biasing means.

10. In a slide rule having a pair of stator elements and a cursor slidable thereover, said cursor having a pair of wedge shape portions having interengaging inclined surfaces, one of said wedge shape portions being slidable with respect to the other, said wedge shape portions, on relative sliding thereof, being expandable and contractible, one of said wedge shape portions being adapted to engage one of said stator elements, means biasing said slidable wedge shape portion in contracting direction, means biasing said slidable wedge shape portion in expanding direction, and means for inactivating said last-named biasing means.

ARTHUR F. ECKEL.
